(57) **CLAIM**

The ornamental design for an inner rim for a food package tray, as shown and described.

DESCRIPTION

FIG. 1 is a top, front, and side perspective view of an inner rim for a food package tray in accordance with a first embodiment of my new design.

FIG. 2 is a bottom, rear, and side perspective view of the inner rim for a food package tray shown in FIG. 1.

FIG. 3 is a top plan view of the inner rim for a food package tray shown in FIG. 1.

FIG. 4 is a bottom plan view of the inner rim for a food package tray shown in FIG. 1.

FIG. 5 is a top, front, and side perspective view of an inner rim for a food package tray in accordance with a second embodiment of my new design.

FIG. 6 is a bottom, rear, and side perspective view of the inner rim for a food package tray shown in FIG. 5.

FIG. 7 is a top plan view of the inner rim for a food package tray shown in FIG. 5; and,

FIG. 8 is a bottom plan view of the inner rim for a food package tray shown in FIG. 5.

The broken lines illustrate environmental structure which forms no part of the claimed design.

1 Claim, 8 Drawing Sheets
